Primary Examiner — Rob Spear*Assistant Examiner* — Carla Wright(57) **CLAIM**

The ornamental design for a cover for an electronic device, as shown and described.

DESCRIPTION

FIG. 1 is a front isometric view of a cover for an electronic device showing our new design;

FIG. 2 is a rear isometric view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a front isometric view of another position of a cover for an electronic device; and,

FIG. 10 is a rear isometric view of another position of a cover for an electronic device.

In the drawings, the broken lines depict unclaimed environment.
